FREDERICK L. BICKEL, OF IVYLAND, PENNSYLVANIA.

APPARATUS FOR DRYING HOSIERY AND THE LIKE.

1,344,612.

Specification of Letters Patent. Patented June 29, 1920.

Application filed May 31, 1919. Serial No. 300,845.

To all whom it may concern:

Be it known that I, FREDERICK L. BICKEL, a citizen of the United States, residing at Ivyland, in the county of Bucks and State 5 of Pennsylvania, have invented certain new and useful Improvements in Apparatus for Drying Hosiery and the like, whereof the following is a specification, reference being had to the accompanying drawings.

10 The invention relates to an apparatus for drying hosiery and the like of the type consisting of a number of flat hollow forms having the configuration of the articles to be dried, and to the interior of which steam is supplied to furnish the necessary heat.

The invention relates more particularly to a drying apparatus having the general characteristics above outlined and, in which the forms are connected in serial relation, 20 so that the steam is caused to flow successively through the forms in its passage through the series. Heretofore, considerable difficulty has been experienced in the operation of such apparatus owing to choking or 25 clogging caused by the trapping of air and water of condensation in the constricted circulatory channels of the comparatively thin forms, thereby preventing the passage of the steam.

30 It is the purpose of my invention to overcome these difficulties. To this end, I have devised means whereby the steam is restricted to passage in a definite direction through each form so as to establish a single 35 avenue of circulation through the series. The invention also comprehends individual means whereby, in the event of the clogging of any of the forms by air and water of condensation, such forms will be temporarily

40 automatically short circuited to permit the passage of the steam to the others of the series, said means being at the same time instrumental in establishing a balanced pressure throughout each of the clogged forms 45 whereby the condensation is given an opportunity to dissipate, as a result of which, such forms are again automatically rendered operative in the normal manner with relation to the series.

50 The structure whereby I attain the ends set forth above will be best understood from the description which follows.

In the drawings, Figure I, is an illustration partly in elevation and partly in section 55 of a portion of a drying apparatus conveniently embodying my invention.

Fig. II, is an end view of one of the forms, and

Fig. III, is a plan sectional view along the plane of the arrows III—III, in Fig. I. 60 The forms 1, are of the hollow type and for convenience of illustration are herein shown as having the configuration of half hose. Said forms are subdivided internally by a median partition 2, to afford definite 65 channels for steam circulation. The base flanges 3, of the forms are bolted to the corresponding flanges 4, of fittings 5, interposed in serial relation in a horizontal line conduit 6, which is communicative, prefer- 70 ably at the left hand end, with a source of steam supply. These fittings are formed with trap pockets 7, in turn subdivided by vertical transverse baffles 8, which virtually constitute extensions of the partitions 2, of 75 the forms proper. Said baffles have their lower ends spaced from the bottoms of the traps to afford by passes which are normally water sealed as shown. The interiors of the fittings are communicative with the 80 forms through the openings 9—9, and a resilient gasket 10, disposed between the flanges 3, and 4, insures a steam tight joint.

The operation of the invention is as follows:

85 The steam enters the conduit 6, at the left and by reason of the normal sealing of the trap 7, is obliged to turn upwardly into the first form and follow the course of the arrows at the left of the median portion 2. 90 After rounding about the upper end of said partition, the steam passes downwardly to the right of the same and into the succeeding section of the conduit 6, and thence to the next form in the series. Any condensa- 95 tion accumulating in the form, drips downwardly by gravity into the trap. When the several traps become filled with water, the overflow is carried off through the conduit 6, and is discharged with the spent steam 100 at the end of the apparatus. By the construction set forth, it is to be noted that the condensation is separately collected from each form and not carried from one form through the succeeding forms before being 105 discharged. In this way clogging of the apparatus is positively prevented in the normal operation of the apparatus.

As steam is initially admitted to the apparatus when cold, the condensation in the 110 forms takes place so rapidly that they become clogged, thereby constituting a tem-

porary barrier to the passage of the steam. When this resistance becomes great enough to overcome that offered by the water seal in the trap, the latter breaks down, thereby 5 permitting the steam to by pass to the opposite side of the baffle 8, and into the next section of the conduit 6. As a result of this action, the pressure on both sides of the diaphragm 2, of the clogged form is equalized 10 so that the obstructing condensation is afforded an opportunity to dissipate and find its way into the trap. As soon as the form is relieved, the trap will re-seal itself and the unit thereafter functioning in the proper 15 manner. By following this same method of reasoning throughout the series, it will be seen that the apparatus will, in a comparatively short time, automatically adjust itself to normal conditions of operation.

20 From the foregoing, it is to be noted that the direction of circulation of the steam through the individual forms is definitely determined and that the passage of the steam through the apparatus, as a whole, is 25 restricted to a single avenue.

Having thus described my invention, I claim:

1. An apparatus for drying hosiery and the like consisting of a number of hollow 30 forms arranged in serial relation; means for normally causing a heating medium to circulate over a definite course through each form and in succession through the series, said means, in the event of the clogging of 35 any of the forms, having capacity to effect the short circuiting of the clogged forms without interrupting the circulation through the remainder of the series.

2. An apparatus for drying hosiery and

the like consisting of a number of hollow 40 forms interposed in serial relation in a steam supply conduit, said forms having individual traps for collecting the water of condensation.

3. An apparatus for drying hosiery and 45 the like consisting of a number of hollow forms interposed in serial relation in a steam supply conduit, said forms having individual water sealed pockets which normally serve as traps for the water of condensation; but which, in the event of the 50 clogging of any of the associated forms, will permit the steam to by pass and supply the remainder of the system.

4. An apparatus for drying hosiery and 55 the like consisting of a number of hollow forms interposed in serial relation in a steam supply conduit, each of said forms having a median partition whereby the steam is obliged to normally follow a definite circulatory path through the form; a trap for collecting the water of condensation, said trap having a transverse baffle forming a continuation of the said median partition of the form, and terminating short 60 of the trap bottom to afford a by pass which is normally sealed by the water of condensation, but which, in the event of the clogging 65 of the form, permits the passage of the steam to supply the remainder of the system.

In witness whereof, I have hereunto signed my name at Philadelphia, Pennsylvania, this twenty-eighth day of May 1919.

FREDERICK L. BICKEL.
